CLAIM

The ornamental design for a gas stove table, as shown and described.

DESCRIPTION

FIG. 1 is a front, right and top perspective view of a gas stove table showing our new design;

FIG. 2 is a rear, left and bottom perspective view thereof;

FIG. 3 is a front elevational view thereof;

FIG. 4 is a rear elevational view thereof;

FIG. 5 is a left side *elevational* view thereof;

FIG. 6 is a right side *elevational* view thereof;

FIG. 7 is a top plan view thereof;

FIG. 8 is a bottom plan view thereof; and,

FIG. 9 is an enlarged *and partial perspective* view of [portion] area 9 in FIG. 1.

The broken lines in the drawings illustrate portions of the gas stove table [which] that form no part of the claimed design.

The dash-dot broken lines encircling area 9 in FIGS. 1 and 9 do not represent actual subject matter and are provided for annotative purposes to show the area of enlargement.

1 Claim, 9 Drawing Sheets

Matter enclosed in heavy brackets [ ] appears in the original patent but forms no part of this reissue; matter printed in italics indicates the additions made by reissue.
